STEAM GENERATOR

Max H. Kuhner, Worcester, Mass., assignor to
 Riley Stoker Corporation, Worcester, Mass., a
 corporation of Massachusetts

Application February 6, 1943, Serial No. 474,913

8 Claims. (Cl. 122—478)

This invention relates to steam generators and more particularly to apparatus capable of utilizing the heat from the combustion of fuel to produce steam and to superheat the steam to a high temperature.

It is one object of the invention to provide a steam generator which will have a large capacity in relation to the floor space occupied.

It is a further object of the invention to provide a steam generator which will be thoroughly dependable in service and capable of superheating steam to unusually high temperatures.

It is a further object of the invention to provide a steam generator having a new and highly efficient arrangement of tubular superheater elements through which the steam will travel in counterflow relation to hot gases of combustion.

It is a further object of the invention to provide a steam generator having a high temperature superheater so arranged and supported as to facilitate installation of the various elements.

It is a further object of the invention to provide a steam generator having a superheater, with a new and advantageous arrangement of water cooled baffles to direct hot gases into counterflow heat-transfer relation with the superheater.

It is a further object of the invention to provide a steam generator having a superheater, with a new and advantageous arrangement for allowing a controlled portion of the hot gases to by-pass the superheater, so that the steam temperature can be controlled.

With these and other objects in view, as will be apparent to those skilled in the art, the invention resides in the combination of parts set forth in the specification and covered by the claims appended hereto.

Referring to the drawings illustrating one embodiment of the invention, and in which like reference numerals indicate like parts,

Fig. 1 is a longitudinal section through a steam generator;

Fig. 2 is a fragmentary longitudinal section taken adjacent one of the side walls;

Fig. 3 is an enlarged fragmentary view showing the means for supporting the high temperature superheater, certain refractory material being removed for clearness of illustration;

Fig. 4 is a section on the line 4—4 of Fig. 3 and Fig. 5 is a section on the line 5—5 of Fig. 3.

The embodiment illustrated comprises an upper transverse steam-and-water drum 10, a lower transverse water drum 11 therebeneath, and a considerable number of transverse rows of upright water tubes 12 connecting the drums to provide

a tube bank. These tubes and drums are mounted within the rear portion of a setting having a front wall 14, a rear wall 15, a roof 16, and two side walls 17 (one only being shown). The front wall 14 is spaced a considerable distance forwardly from the tube bank. The lower front portion of the setting is utilized as a combustion chamber 18 provided with a rear wall 20 having a burner opening 21 therein for the introduction of a suitable fuel, such as gas or oil. This wall 20 is located forwardly with respect to the lower drum 11, and this drum is elevated sufficiently to allow ready access to the burner opening 21.

The combustion chamber 18 is preferably cooled by suitable water wall tubes adjacent some or all of its walls. For this purpose a header 23 is provided at the bottom of the rear wall 20, and a header 24 is provided at the bottom of each side wall 17, these headers 24 being connected to the adjacent ends of the header 23. Water is supplied to the header 23 from the lower drum 11 by a row of downcomer tubes 25 located behind the wall 20 and offset laterally from the burner opening 21. From each of the headers 24 a row of water wall tubes 27 extends upwardly along the corresponding side wall 17 to an upper header 28 (Fig. 2) which is connected to the upper drum 10 by a row of riser tubes 29. For clearness of illustration, only the lower portions of the side water wall tubes 27 are shown in Fig. 1. A header 31 is mounted adjacent the front wall 14 and intermediate the height of this wall. A row of water tubes 32 extends forwardly from the rear header 23 to the front wall 14 and thence upwardly along this wall to the header 31, the lower portions of these tubes supporting refractory material 33 to provide a floor for the combustion chamber. From the header 31 two rows of water tubes 34 extend upwardly and rearwardly to connect with the front portion of the upper drum 10, the tubes in each of these rows being spaced apart rather widely. A row of water tubes 36 extends upwardly from the rear header 23 along the rear wall 20 and thence upwardly and forwardly to a transverse header 37 which is spaced rearwardly from the front wall 14. These tubes 36 support refractory material 38 to provide a roof for the combustion chamber. From the header 37 a row of water tubes 40 extends upwardly and rearwardly to connect with the front portion of the upper drum 10, these tubes 40 being positioned between the tubes 34 in the lower row. From the lower drum 11 a row of water tubes 41 extends forwardly between the tubes 36 beneath the combustion chamber roof 38 and then loops upwardly and

rearwardly to a position slightly in front of the tube bank 12, whence it extends upwardly and connects with the front portion of the upper drum 10 in the same line as the upper row of tubes 34.

The hot gases leaving the combustion chamber 19 are directed into contact with steam superheating surfaces and then into the lower portion of the water tube bank 12. For this purpose the refractory 38 is extended forwardly and upwardly along the tubes 36 to the header 37 to cooperate with the front wall 14 in defining a passage 43 which leads upwardly from the front portion of the combustion chamber and between the front portions of the water tubes 34. A baffle 44 extends upwardly and rearwardly from the headers 37 along the water tubes 40 and the lower row of water tubes 34 to cooperate with the roof 16 in defining a rearwardly tapering passage 45. The water tubes 41 support an upright baffle 47 having a forward extension 48 at its lower end which cooperates with the baffle 44 in defining a forwardly tapering passage 49 located beneath the passage 45. These passages 45 and 49 communicate between the baffle 47 and the rear edge of the baffle 44. Beneath the baffle 48 there is provided a rearwardly extending passage 51 which leads to the lower portion of the tube bank 12. The passages 49 and 51 communicate between the roof 38 and the front edge of the baffle 48. The baffle 47 is spaced forwardly from the tube bank 12 to form a passage 52 which leads downwardly from the rear end of the upper passage 45 to the lower passage 51, this passage 52 having a damper 53 therein. A baffle 55 extends downwardly adjacent the front portion of the tube bank 12 from the upper drum 10 and terminates somewhat above the lower drum 11 to allow the gases to flow into the tube bank and then upwardly to an outlet duct 56 behind the upper drum. The upwardly flowing gases are deflected into a tortuous course by means of a series of staggered transverse baffles 57.

Before the gaseous products of combustion reach the tube bank 12 they are utilized to superheat the steam. For this purpose a high temperature superheater 59 is mounted in the gas passage 45, and a low temperature superheater 60 is located in the passage 49. Each of these superheaters comprises a series of laterally spaced tubes each formed with a considerable number of upright loops providing a sinuous construction. The front end of the low temperature superheater 60 is connected to the steam space of the drum 10 by means of a row of tubes 61 which extend downwardly in front of the baffle 47. The rear ends of the two superheaters are joined by a row of upright tubes 63, and the front end of the high temperature superheater 59 is connected directly to a transverse outlet header 64 located above the roof 16. It will be apparent that the general direction of travel of the steam will be rearwardly through the low temperature superheater 60 and then forwardly through the high temperature superheater 59, in counterflow heat transfer relation to the gases flowing through the passages 45 and 49.

In order to support the high temperature superheater 59 and the portion of the roof 16 adjacent thereto I provide several transverse bars 66 each shaped as an inverted T in cross-section, the ends of the bars being suitably connected to the supporting framework of the boiler. The flanges of the bars 66 support the ends of beams 67 in the form of upright plates with their lower edges welded to the superheater tubes 59, as best shown

in Fig. 3. Certain loops 69 of the tubes 59 are extended upwardly and pass over the bars 66, these loops being slightly offset laterally from the beams 67, as shown in Fig. 4, to avoid interference. The low temperature superheater 60 may be suspended in any suitable manner from the water tubes 34 and 40.

The operation of the invention will now be apparent from the above disclosure. A suitable fuel, such as gas or oil, is introduced through the opening 21 and burned in suspension in the combustion chamber 19. Heat from the burning fuel is radiated to the surrounding water wall tubes, thus generating steam which is delivered to the drum 10, where the water is separated from the steam. The steam flows from the drum 10 through the tubes 61 to the front end of the superheater 60, rearwardly through this superheater, upwardly through the tubes 63 to the rear end of the superheater 59, and then forwardly through this superheater 59 to the outlet header 64. The gaseous products of combustion flow upwardly from the combustion chamber 19 through the passage 43 and then rearwardly through the passages 59. The gases then divide, a portion flowing rearwardly over the top of the baffle 47 and downwardly through the passage 52, and the remainder flowing downwardly in front of the baffle 47, forwardly through the passage 49, and then downwardly and rearwardly through the passage 51 to rejoin the gases from the passage 52. The combined gases then enter the water tube bank 12 and flow upwardly in contact therewith until they finally escape through the outlet duct 56. The flow of the hot gases past the two superheaters is opposite to the general direction of the steam flow through the superheaters resulting in efficient transfer of heat to the steam. By adjusting the damper 53 the operator can control the flow of the gases in the passage 52, and thus direct a greater or less proportion of the gases into contact with the low temperature superheater 60. In this manner it is possible to regulate the final temperature of the steam delivered to the outlet header 64.

The various baffles are all supported and cooled by water tubes through which a rapid natural circulation is maintained. Such a baffle construction is highly effective and it will have a long life of useful service. The arrangement of the two superheaters is particularly compact, it provides a large superheater surface, and it permits a gradually decreasing cross-sectional area for the gas passages to ensure maintenance of adequate gas velocities despite reduction in temperature and volume. Because of the lack of appreciable convection heating surface ahead of the superheaters, the gases will reach the superheater 59 at a high temperature, and it is feasible to superheat the steam to a high temperature. The high temperature superheater 59, and particularly the front portion thereof, should be made of a high quality heat resisting metal or alloy. If after long service a portion of this upper superheater should require replacement, it is a simple matter to cut the adjacent loops 69 and remove the desired sections upwardly, whereupon a new section can be lowered into position and the ends thereof welded to the severed ends of the loops.

Having thus described my invention, what I claim as new and desire to secure by Letters Patent is:

1. A steam generator comprising a setting, a transverse steam-and-water drum in the rear

portion of the setting, a transverse water drum beneath the steam-and-water drum, a considerable number of transverse rows of upright water tubes connecting the drums to provide a tube bank, a combustion chamber in the lower portion of the setting, a high-temperature superheater in the upper portion of the setting in front of the tube bank, a low-temperature superheater beneath the high-temperature superheater, means to deliver steam from the steam-and-water drum to the low-temperature superheater and thence to the high-temperature superheater, and means to direct hot gases from the combustion chamber into contact successively with the high-temperature superheater, the low-temperature superheater, and the tube bank.

2. A steam generator comprising a setting, a transverse steam-and-water drum in the rear portion of the setting, a transverse water drum beneath the steam-and-water drum, a considerable number of transverse rows of upright water tubes connecting the drums to provide a tube bank, a combustion chamber in the lower portion of the setting, a high-temperature superheater in the upper portion of the setting in front of the tube bank, a low-temperature superheater beneath the high-temperature superheater, means to deliver steam from the steam-and-water drum to the low-temperature superheater and thence to the high-temperature superheater, a passage to conduct hot gases upwardly from the combustion chamber and in front of the low-temperature superheater to the high-temperature superheater, and means to direct the gases downwardly from the high-temperature superheater to the low temperature superheater and thence rearwardly to the said tube bank.

3. A steam generator comprising a setting, a transverse steam-and-water drum in the rear portion of the setting, a transverse water drum beneath the steam-and-water drum, a bank of upright water tubes connecting the drums, a combustion chamber in the lower portion of the setting, a high-temperature superheater in the upper portion of the setting in front of the tube bank, a low-temperature superheater beneath the high-temperature superheater, means to deliver steam from the steam-and-water drum to the front portion of the low-temperature superheater for flow in a generally rearward direction therethrough and thence to the rear portion of the high-temperature superheater for flow in a generally forward direction therethrough, and means to direct hot gases from the combustion chamber upwardly and then rearwardly in contact with the high-temperature superheater, downwardly and then forwardly in contact with the low-temperature superheater, and downwardly and rearwardly for eventual flow in contact with the tube bank

4. A steam generator comprising a setting, a transverse steam-and-water drum in the rear portion of the setting, a transverse water drum beneath the steam-and-water drum, a bank of upright water tubes connecting the drums, a combustion chamber in the lower portion of the setting, a high-temperature superheater in the upper portion of the setting in front of the tube bank, a low-temperature superheater beneath the high-temperature superheater, each of said superheaters including a series of laterally spaced tubes each formed with a considerable number of upright loops providing a sinuous construction, means to deliver steam from the steam-and-water drum to the front portion of the low-temperature superheater for flow in a generally rearward

direction therethrough and thence to the rear portion of the high-temperature superheater for flow in a generally forward direction therethrough, and means to direct hot gases from the combustion chamber upwardly and then rearwardly in contact with the high-temperature superheater, downwardly and then forwardly in contact with the low-temperature superheater, and downwardly and rearwardly for eventual flow in contact with the tube bank.

5. A steam generator comprising a setting, a transverse steam-and-water drum in the rear portion of the setting, a transverse water drum beneath the steam-and-water drum, a bank of upright water tubes connecting the drums, a combustion chamber in the lower portion of the setting, a rearwardly tapering upper passage in the upper portion of the setting in front of the tube bank, a forwardly tapering lower passage beneath the upper passage, the rear ends of the two passages being connected, a passage connecting the combustion chamber with the front end of the upper passage, a passage connecting the front end of the lower passage with the tube bank, a high-temperature superheater in the upper passage, a low-temperature superheater in the lower passage, and means to deliver steam from the steam-and-water drum to the front portion of the low-temperature superheater for flow in a generally rearward direction therethrough and thence to the rear portion of the high-temperature superheater for flow in a generally forward direction therethrough.

6. A steam generator comprising a setting, a transverse steam-and-water drum in the rear portion of the setting, a transverse water drum beneath the steam-and-water drum, a bank of upright water tubes connecting the drums, a combustion chamber in the lower portion of the setting, a rearwardly directed upper passage in the upper portion of the setting in front of the tube bank, a forwardly directed lower passage beneath the upper passage, the rear ends of the two passages being connected, a passage extending upwardly from the combustion chamber to the front end of the upper passage, a passage connecting the front end of the lower passage with the tube bank, a by-pass connecting the rear end of the upper passage with the tube bank, a damper in the by-pass, a high-temperature superheater in the upper passage, a low-temperature superheater in the lower passage, and means to deliver steam from the steam-and-water drum to the front portion of the low-temperature superheater for flow in a generally rearward direction therethrough and thence to the rear portion of the high-temperature superheater for flow in a generally forward direction therethrough.

7. A steam generator comprising a setting, a transverse steam-and-water drum in the rear portion of the setting, a transverse water drum beneath the steam-and-water drum, a bank of upright water tubes connecting the drums, a combustion chamber in the lower portion of the setting, a rearwardly directed upper passage in the upper portion of the setting in front of the tube bank, a forwardly directed lower passage beneath the upper passage, the rear ends of the two passages being connected, a passage extending upwardly from the combustion chamber to the front end of the upper passage, a passage extending from the front end of the lower passage downwardly and rearwardly to the lower portion of the tube bank, a by-pass extending from the

rear end of the upper passage downwardly in front of the tube bank to the lower portion thereof, a damper in the by-pass, a high temperature superheater in the upper passage, a low-temperature superheater in the lower passage, and means to deliver steam from the steam-and-water drum to the front portion of the low-temperature superheater for flow in a generally rearward direction therethrough and thence to the rear portion of the high-temperature superheater for flow in a generally forward direction therethrough.

8. A steam generator comprising a setting having walls and a roof, a transverse steam-and-water drum in the rear portion of the setting, a transverse water drum beneath the steam-and-water drum, a bank of upright water tubes connecting the drums, a combustion chamber in the lower portion of the setting having a rear wall, a transverse header above the combustion chamber and spaced from the front wall of the setting, a row of water tubes extending forwardly from the upper portion of the said rear wall to the header, refractory material supported by the said row of tubes providing a roof for the combustion chamber, a row of water tubes extending upwardly and rearwardly from the header to the

steam-and-water drum, a baffle extending upwardly and rearwardly from the header adjacent the last-mentioned water tubes to cooperate with the roof of the setting in defining an upper passage having its front end connected directly with the combustion chamber therebeneath to receive hot gases rising therefrom, an upright baffle behind the first-mentioned baffle and having a forward extension at its lower end beneath the first-mentioned baffle to cooperate therewith in defining a lower passage having its front end connected directly with the bank of water tubes, a row of water tubes arranged in supporting relation to the last-mentioned baffle, the rear ends of the two passages communicating in front of the upright baffle, a high-temperature superheater in the upper passage, a low-temperature superheater in the lower passage, and means to deliver steam from the steam-and-water drum to the front portion of the low-temperature superheater for flow in a generally rearward direction therethrough and thence to the rear portion of the high-temperature superheater for flow in a generally forward direction therethrough.

MAX H. KUHNER.
